Application April 18, 1952, Serial No. 19,396

Term of patent 14 years

(Cl. D29—23)

To all whom it may concern:

Be it known that we, Louis F. Mancini and Doris Marie Bauernfeind, citizens of the United States, residing at Bradshaw, Maryland, and Middle River, Maryland, respectively, have invented a new, original, and ornamental Design for a Religious Plaque, for which the following is a specification, reference being had to the accompanying drawing, forming a part thereof, in which:

Figure 1 is a front elevational view of a religious plaque, showing our new design; and

Figure 2 is a side elevational view thereof.

The essential features of our design reside in those portions shown in full lines.

We claim:

The ornamental design for a religious plaque, as shown and described.

LOUIS F. MANCINI.

DORIS MARIE BAUERNFEIND.
